UNITED STATES PATENT OFFICE.

GEORGE GEDDES, OF FAIR MOUNT, ASSIGNOR TO CULVER G. THYNG, OF OLEAN, NEW YORK.

DESIGN FOR SHAFTS FOR TWO-WHEELED VEHICLES.

SPECIFICATION forming part of Design No. 19,523, dated December 24, 1889.

Application filed July 3, 1888. Serial No. 278,969. Term of patent 14 years.

To all whom it may concern:

Be it known that I, GEORGE GEDDES, a citizen of the United States, residing at Fair Mount, in the county of Onondaga, State of New York, have invented and produced a new and original Design for Shafts for Two-Wheeled Vehicles, of which the following is a specification, reference being had to the accompanying drawing, forming a part thereof.

10 The leading feature of my design consists in a central depressed portion of the shaft, elevated extremities thereon, an inclined plane between said depressed portion and one of said elevated extremities, and a compoundly-curved plane between said depressed portion and the opposite elevated extremity.

15 The central portion A of the shaft is disposed in a depressed and substantially a horizontal plane and the separate extremities 20 a and D are raised above said depressed plane. Between its rear extremity a and said depressed part A the shaft is disposed in an inclined plane B, which gradually rises to the plane of said extremity.

The forward extremity D of the shaft is 25 disposed in substantially a horizontal plane, and between the same and said depressed plane the shaft is disposed in a compoundly-curved plane C.

It will thus be seen that my design embodies the union of curved and straight lines in a peculiar form, causing the shaft to present a novel and pleasing effect.

Having thus fully set forth my invention, 30 what I claim is—

35 The design for shafts for two-wheeled vehicles herein shown and described.

In testimony whereof I have hereunto signed my name, in the presence of two attesting witnesses, at Syracuse, in the county of Onondaga, in the State of New York, this 30th day 40 of June, 1888.

GEORGE GEDDES.
